UNITED STATES PATENT OFFICE

2,330,626

ELEVATOR FOR REPETITION AND
AUTOMATIC FIREARMSGino Revelli, Rome, Italy; vested in the Alien
Property CustodianApplication October 6, 1939, Serial No. 298,323
In Italy October 31, 1938

2 Claims.

(Cl. 42—6)

The repetition and automatic fire-arms (guns, machine-guns and the like), using cartridge loaders in which the cartridges are displaced by a translation motion perpendicular to their axis and contained in the plane of the loader, are provided with spring elevator devices pushing the whole of the cartridges towards the position where they are taken by the bolt to be thrust into the barrel.

The elevators of cartridges known till now have all the inconvenience not to support in their exact predetermined position the cartridges of the loader as they exercise a variable pushing strain applied in a variable position to the cartridge casing in contact with the pushing member of the elevator, no mechanism having been till now suggested capable of keeping its exact functioning even after a high number of shots of the fire-arm.

The use of modern materials and processes of production for gun-barrels has doubled and tripled the life and consequently the whole life of a fire-arm, so that the elevator device has to be constructed in such a way to be kept in perfect conditions of functioning for the life of the barrel, that is till the arm has to be sent back to a workshop to have the barrel repaired or changed.

One of the devices most known and used at large comprises an elevator consisting of a simple lever of third kind anteriorly fulcrumed with respect to the loader stressed at an intermediary point of its length by a spring preferably laminated bearing against the bottom cartridge of the loader with an arcuated end, the shape of which has the object to keep as long as possible unvaried the position of the elevator's lever against the cartridge while the position of translation of the cartridge varies within the loader. Said device, when for instance applied to the Italian repetition gun Mod. 1891 often causes the obstruction of the last cartridge which may be not well held between the curved flanges of the loader.

Another device known in different forms of realisation comprises a Nuremberg shear system operated by a spring lodged under the loader. This device has the inconvenience to be very cumbersome consequently not adapted for repetition and automatic portable arms.

Another system also known comprises a lever system shaped as an articulated parallelogram, two sides of which being of a great length and the other two of a relatively very short length. The control of the elevation by means of this

mechanism becomes inexact after a few shots owing to the strong influence exercised on the position of the member of contact of the elevator due to light plays in the pivots.

Said inconveniences are removed by the present invention providing an elevator consisting of two levers fulcrumed on pivots near to one another preferably placed on the front of the loader, one of said levers (the main one) being stressed to rotate around its own fulcrum by a spring conveniently located; the second lever (secondary lever) being stressed to rotate by the action of the main spring through a pin and groove mechanism or the like. The free ends of the two levers are provided with a follower or support member for the bottom cartridge of the loader preferably comprising a flat ruler-like follower, connected by a pivot to the end of one of the levers and simply bearing on the end of the other lever.

The invention is illustrated in a preferred form of realisation in the accompanying drawing in which:

Fig. 1 shows an elevator according to the invention applied to a repetition gun;

Fig. 2 shows the same elevator in another position.

With reference to the drawing the elevator comprises a main lever 1 fulcrumed on the pin 2 conveniently fixed to the arm, which is partially indicated by way of small strokes. A spring 3 acts on the lever 1 to make it rotate around its own fulcrum, so that the back part of the ruler or follower 4 supporting the cartridges 5 contained in the loader 6 may be raised. The lever 1 is articulated with the ruler 4 by means of the pivot 7. The prolongations 8 of the lever 1 beyond the pivot 7 cooperates with the back end 9 of the member 4 so that this member is prevented from forming with the lever 1 an angle greater than the predetermined maximum one.

On the fixed pivot 10 there is fulcrumed the secondary lever 11, provided with a pin 12 co-operating with the profile surface 13 of the lever 1. The profile surface 13 might be substituted by a groove of corresponding form. The end 14 of the lever 11 co-operates with the ruler 4 sliding on its lower surface 15 which may be flat or conveniently shaped. The ruler 4 is kept bearing against the point 14 of the lever 11 by the pressure of the overlying cartridges 5, against which the ruler 4 is pushed by the lever 1 operated by the spring 3.

According to a characteristic of the present invention both levers 1 and 11 are curved, and

substantially bent at right angle so that they may be disposed with the minimum encumbrance possible on the front and downwards with respect to the cartridge loader inserted into the arm, nearly embracing the anterior, inferior angle of encumbrance of the loader provided with all its cartridges. This disposition of the elevator is extraordinarily advantageous since the advantage of an elevating mechanism of exact, durable functioning is coupled to the one that the mechanism may be substituted for the various types of elevator used now in repetition and automatic fire-arms without requiring greater room and consequently costly adaptations.

During the movement of elevation, that is during the passage from the position illustrated in Fig. 1 to the one illustrated in Fig. 2, the lifting plate 4 has to be kept bearing on the point 14 of the lever 11 assuming at the same time the position of the inferior generatrix of the casing of the bottom cartridge as it is pre-established for each determined arm. Consequently should the casings of the cartridges 5, as illustrated in Fig. 1, be cylindrical the ruler 4 must be displaced by remaining parallel to itself; while if the casing of the cartridges is conical, the ruler 4 has correspondingly to vary inclination while it is raised. This is obtained by means of a convenient shape of the surfaces 13 and 15, which may be easily worked with high precision and hardened in such a way that no remarkable trace of wear may appear even after a long period of use.

With the elevator according to the present invention the cartridge supporting ruler 4 is constantly kept bearing, respectively pivoted, on two reciprocally distant points of which one is on the circle arc A—B, run by the pivot 1, the other on the circle arc C—D run by the end 14 of the secondary lever 11. In that way the best possible guide is obtained for the cartridges 5 within the

loader 6 during the whole stroke of the elevator. By positioning the pivot 2 of lever 1 substantially level with the mid point of the curve A—B the longitudinal or sliding movement of the lifter 5 against the cartridge is reduced to a minimum.

The present invention has been illustrated and described in a preferred form of realisation, but it is understood that constructive changes may be inserted therein without surpassing the limits of protection of the present industrial patent.

I claim:

1. A cartridge feeding mechanism for fire-arms including an upwardly extending magazine adapted to receive a row of cartridges, a lifting plate disposed beneath the cartridges in the magazine, a lever of approximately L-shape provided with a cam surface thereon and having its rear end pivotally connected to the plate adjacent the rear end of the said plate and its forward end pivotally connected to the fire-arm, an arcuate shaped lever having its front end pivotally connected to the fire-arm and its rear end slidably engaging the lifting plate, a projection extending from said second-named lever for slidable engagement with said cam surface and means for turning said first named lever about its pivotal mounting to raise the rear end of said first named lever, and by means of said cam surface and projection to turn said arcuate shaped lever about its mounting and raise the rear end thereof, said cam surface being so formed as to maintain raising contact with said projection to cause the rear end of said levers to travel together and to maintain the lifting plate parallel to the fire-arm throughout the entire range of lifting movement.
2. The mechanism as specified in claim 1 wherein said first named lever is pivoted at a point substantially level with the mid point of the path of movement of the rear end of said first named lever.
